DESIGN FOR A CONTAINER FOR PERFUME BOTTLE OR SIMILAR ARTICLE

John D. Buckingham, Chicago, Ill., assignor to Lucien Lelong, Inc., Chicago, Ill., a corporation of Illinois

Application January 5, 1942, Serial No. 105,022

Term of patent 14 years

To all whom it may concern:

Be it known that I, John D. Buckingham, a citizen of the United States and a resident of the city of Chicago, in the county of Cook and State of Illinois, have invented a new, original, and ornamental Design for a Container for Perfume Bottle or Similar Article, of which the following is a specification, reference being had to the accompanying drawing, forming a part thereof.

On the drawing:

Figure 1 is a top plan view of the container for perfume bottle, or similar article, showing my new design, and

Figures 2, 3, 4 and 5 are elevational views thereof.

I claim:

The ornamental design for a container for perfume bottle or similar article, as shown.

JOHN D. BUCKINGHAM.
